240,803

STACKING ELEMENT FOR CONTAINERS OR THE LIKE

Stanley Bell, Sands Point, N.Y., assignor to Attwood
Products, Farmingdale, N.Y.

Filed Oct. 31, 1974, Ser. No. 519,618

Term of patent 14 years

Int. Cl. D9—99

U.S. Cl. D9—294

FIG. 1

FIG. 2

FIG. 3

FIG. 4

FIG. 5

FIG. 6

FIG. 1 is a front elevational view of a stacking element for containers or the like showing my new design;

FIG. 2 is a rear elevational view;

FIG. 3 is a side elevational view as seen from the right of FIG. 2;

FIG. 4 is a side elevational view showing the side opposite that seen in FIG. 3;

FIG. 5 is an end elevational view; and

FIG. 6 is an end elevational view showing the end opposite that seen in FIG. 5.

I claim:

The ornamental design for a stacking element for containers or the like, substantially as shown.
